UNITED STATES PATENT OFFICE

2,617,684

HYDRAULIC HOIST FOR TRUCK BODIES

Thomas L. Workman and Harold B. Workman,
Woodburn, Oreg.

Application November 22, 1949, Serial No. 128,692

1 Claim. (Cl. 298—22)

1

This invention relates to a hydraulic hoist for truck bodies.

An object of this invention is to provide an improved hydraulic hoist for truck bodies which embodies a pair of hydraulic operators pivotally mounted on the opposite sides of the chassis and pivotally connected to the body.

Another object of this invention is to provide improved brackets or hangers for securing the hydraulic operators to the truck frame or chassis and to the truck body.

With the above and other objects in view, our invention consists in the arrangement, combination and details of construction disclosed in the drawings and specification, and then more particularly pointed out in the appended claim.

In the drawings,

Figure 1 is a detail side elevation of a hydraulic operator secured to a truck frame and body, the latter being fragmentarily shown, constructed according to an embodiment of this invention.

Figure 2 is a fragmentary sectional view taken on the line 2—2 of Figure 1.

Figure 3 is a fragmentary sectional view taken on the line 3—3 of Figure 1.

Figure 4 is a fragmentary sectional view taken on the line 4—4 of Figure 1.

Figure 5 is a fragmentary sectional view taken on the line 5—5 of Figure 1.

Figure 6 is a fragmentary sectional view taken on the line 6—6 of Figure 1.

Figure 7 is a fragmentary sectional view taken on the line 7—7 of Figure 5.

Referring to the drawings, the numeral 10 designates generally the frame or chassis of a truck which has pivotally mounted on the rear portion thereof a body 11. The body 11 has secured to the lower side thereof transverse channel members 12, and a pair of longitudinal channel members 13 are secured to the channel members 12.

The chassis 10 includes a pair of longitudinal side channel members 14 and the rear ends of the channel members 14 have secured thereto L-shaped brackets 15 formed with bearing bosses 16. A longitudinally curved bracket 17 is secured by fastening means 18 to the body channel members 13, and each bracket member 17 is formed of an inner plate 19, having marginal flanges 20.

A bracing web 21 is disposed between the outer flanges 20 and terminates at its lower end in a bearing boss 22 through which a pivot pin 23 engages. The pin 23 also engages through the bearing boss 16.

The body 11 is adapted to be raised or lowered

with respect to the chassis 10 by means of a pair of hydraulic operators generally designated as 24. The operators 24 include a hydraulic cylinder 25 having a rear head or wall 26, and a forward wall or head 27. The wall or head 27 is disposed in a counterbore 28 formed in the forward end of the cylinder 25, and the head 27 is secured within the counterbore 28 by means of a split locking ring 29 engaging in an annular groove 30 formed in the cylinder 25.

The cylinder 25 is rockably secured to the side channel member 14 by means of a bracket generally designated as 31. The bracket 31 includes a vertically disposed plate 32 and a substantially Z-shaped plate 33. The Z-shaped plate 33 has one portion 34 thereof disposed in face abutting relation to the plate 32 and the two plates 32 and 34 are secured to the channel member 14 by fastening means 35.

20 The inner plate 32 is formed at its upper end with outwardly flared guide 36 which is adapted to guide the body channel member 13 when the body is lowered to a substantially horizontal position. The Z-shaped member 33 includes an outer plate 37 disposed in spaced parallel relation with the lower portion of the plate 32 and a pivot pin 38 engages through the two plates 32 and 37.

25 Figure 2 is a fragmentary sectional view taken on the line 2—2 of Figure 1. Figure 3 is a fragmentary sectional view taken on the line 3—3 of Figure 1. Figure 4 is a fragmentary sectional view taken on the line 4—4 of Figure 1. Figure 5 is a fragmentary sectional view taken on the line 5—5 of Figure 1. Figure 6 is a fragmentary sectional view taken on the line 6—6 of Figure 1. Figure 7 is a fragmentary sectional view taken on the line 7—7 of Figure 5.

A bearing sleeve 39 is fixed as by welding 40 or other suitable fastening means to the end member 26 of the cylinder 25, and the pin 38 loosely engages through the sleeve 39. The cylinder 25 is adapted to be connected to a source of fluid pressure supply by means of a supply pipe line 41.

30 A piston, generally indicated at 42, is slidably mounted in cylinder 25. The piston 42 includes a pair of plates 43 and 44 with a cup-shaped gasket or sealing member 45 clamped by means of a clamping nut 46. The clamping nut 46 is threaded onto a reduced diameter stud 47 carried by a piston rod 48. The piston rod 48 slidably engages the cylinder head 27 and has secured to the forward end thereof a bearing sleeve or cross-head 49 which pivotally engages a body bracket generally designated as 50.

35 The bracket 50 is formed of an inner plate 51 and a substantially Z-shaped plate 52. The Z-shaped plate 52 includes an inner plate 53 secured to the plate 51 and to the longitudinal body channel member 13 by fastening means 54. The Z-shaped member 52 includes an outer plate 55 bearing against the outer end of the sleeve or crosshead 49, and a pivot pin 56 is loosely extended through the plates 51 and 55 and the crosshead 49.

40 In the use and operation of this operator, the

two cylinders 25 are connected to a source of liquid pressure supply by the pipe line 41 which is connected to the rear portion of the cylinder 25. When liquid is forced into the cylinder 25 the piston 43 will be forced outwardly and the body 11 will be raised to the desired angular position with respect to the chassis 10.

We do not mean to confine ourselves to the exact details of construction herein disclosed, but claim all variations falling within the purview of the appended claim.

What we claim is:

In a truck having a horizontal frame and a body, a bracket on said body, means hingedly securing said bracket to the frame at and below the extreme end thereof, means for swinging the body on the frame having a bottom normally parallel to said frame, said means comprising a pair of hydraulic cylinders, a bearing sleeve on one end of each cylinder, a bracket including an apertured flat plate and an offset plate having an aperture aligned with the aperture in said flat plate secured to each side of said frame, a pivot pin extending through the apertures of each bracket and an associated bearing sleeve for pivotal mounting of said cylinder on said frame, a piston in each cylinder, a piston rod connected to each piston, a bearing sleeve carried by the outer end of each piston rod, a bracket carried by each side of said body including an apertured flat plate and an offset plate having an aperture aligned with the aperture in said last mentioned flat plate, and a pivot pin extending through the

apertures in each of said last mentioned brackets and its associated bearing sleeve for pivotal connection of said piston rods to said body, each of said last mentioned brackets being secured to said body at an acute angle relative to said normally horizontal bottom, each of said first mentioned flat plates including an outwardly flared arcuate guide at its upper end for aligning said body when returned to horizontal position.
